Primary Examiner—Stacia Cadmus

(57) **CLAIM**

The ornamental design for an automotive wheel, as shown and described.

DESCRIPTION

FIG. 1 is a perspective view of an automotive wheel showing my new design; and,

FIG. 2 is a front elevational view of an automotive wheel showing the design.

The phantom (broken) lines showing the environment are for illustrative purposes only, and form no part of the claimed design.

1 Claim, 2 Drawing Sheets

FIG. 1

FIG. 2
